EUGENE W. SCHELLENTRAGER, OF SHAKER HEIGHTS, OHIO, ASSIGNOR TO ATLAS BOLT
& SCREW COMPANY, OF CLEVELAND, OHIO

PUSHER FOR RETORT OVENS

Application filed January 5, 1931. Serial No. 506,654.

My invention relates to devices for removing substances from retort ovens.

An object of my invention is to provide a simple and efficient means for removing substances from retort ovens.

Another object of my invention is to provide a simple and efficient means to loosen substances from the floors of retort ovens and at the same time push the same out of the ovens.

Another object of my invention is to provide a ram structure of sufficient strength and rigidity to withstand obstructions encountered in the ovens without deforming the ram structure detrimentally.

Another object of my invention is to provide adjustment for the head on the ram so that the bottom of the head can be adjusted to different heights of bottoms of ovens as well as to different relations between the bottom of the head and the floor of an oven so that the bottom of the head can move over the floor of an oven either on actual contact therewith or various distances from the same.

Another object of my invention is to provide an anchoring means for the ram operating cable on the ram and to make this anchoring means adjustable to also serve the purpose of taking up slack in the cable.

Another object of my invention is to provide an edge at the bottom and forwardly of the head to more effectively loosen substance on the floor of ovens.

Another object of my invention is to provide an automatic power cut out means to prevent the ram from moving beyond desired limits in case an operator neglects to stop the cable operating power means.

Other objects will appear in this specification or will become obvious or apparent or will suggest themselves upon an inspection of the accompanying drawings and of this specification.

Substances treated in retort ovens must be removed from the same which is usually done by devices commonly called pushers which have a ram structure movable to enter the oven at one end and push substances out through the other end.

In many instances, cracking crude oil for instance, substances adhere more or less to the floors of ovens and usually must or at least should be removed before a new charge is entered to avoid contamination or for other reasons and the ram in such removals often encounters serious obstructions such as caked substance or even heavy fluidic substances adhering tightly and not easily removable.

My invention aims to provide the necessary means to effectively and efficiently remove substances from such retort ovens.

For the purpose of illustrating my invention but not for limitation purposes, I have shown in the accompanying drawings and specifically describe in this specification one type of apparatus whereby my invention can be carried out but I am aware that my invention can be carried out with other apparatus.

In the accompanying drawings mentioned:

Fig. 1 is a plan view of a pusher embodying my invention and shows a pusher to travel on a horizontal track in front of a series of wide retort ovens having horizontal floors and a ram movable longitudinally thereon and having a head adapted for the ovens.

Fig. 2 is a side view of the pusher shown in Fig. 1.

Fig. 3 is a front end view partly in section of the pusher shown in Fig. 1.

Fig. 4 is a transverse section taken in a vertical plane indicated by the line 4 in Fig. 2.

Fig. 5 is a longitudinal section taken in a vertical plane indicated by the line 5 in Fig. 1.

Similar reference characters refer to similar parts throughout the views.

The general framing of the pusher is supported on the paired track wheels 10 and 11 running on the tracks 12 and 13 laid in front of a battery of retort ovens so that the pusher can be moved opposite or in front of any one of the ovens; in this instance by the motor A in driving relation with one of the wheels 10 and 11 and controlled by the rheostat B in the cab C sidewise adjacent to the framing of the pusher.

The ram comprises the head D and the stem E.

The stem is built up of two longitudinal,

sidewise or laterally spaced I beams 14 and 15 (best seen in Fig. 4) securely latticed by the squarely disposed lattice members 16 and the oppositely inclined lattice members 17 to provide rigidity in the stem.

5 The vertically disposed plate 18 forms a part of the head and is of a length a little less than the width of the oven 19 and is secured to the ends of both of the I beams 14 and 15 by means of the clip angles 20 and extends transversely thereof. The gusset plates 20a are provided to stiffen and maintain the angular relation between the plate 18 and the ends of both I beams.

10 The channel iron 21a forms a part of the head and extends substantially to the full length of the plate 18 and is located along the upper edge thereof and permanently secured in place thereon. The back of the web of the channel iron is in abutment on the forward face of the plate and the legs of the channel extend forwardly of the plate.

15 The channel iron 21 forms a part of the head and extends substantially to the full length of the plate 18 and is located along the lower edge thereof. The back of the web of the channel iron 21 is in abutment on the forward face of the plate and the legs of the channel extend forwardly of the plate.

20 The bolts 22 extend through the web of the channel 21 and through elongated slots in the plate 18 to provide an adjusting means whereby the bottom of the head can be adjusted vertically into alignment with the top of the bench 23, or the level of the floor in the oven 19, or to any vertical relation to the top of the bench or the floor of the oven within the range of the adjusting means. The nuts 24 retain the channel iron 21 in position on the plate 18 upon tightening thereof after adjustment.

25 It is observed that the plate 18 and the channel irons thereon are disposed vertically to form a substantially square abutment on substance in the oven during a pushing operation of the head so that substance can be pushed out of the oven effectively.

The square abutment mentioned may be varied to an inclined abutment but such inclination should not be carried to a degree which would permit substances to be directed over the top of the head or unduly crowded to the floor of the oven during a pushing operation of the head.

30 The forwardly extending legs of the channel irons assist to prevent upward movement of substance during a pushing operation of the head and the forward end 25 of the lower leg of the channel iron 21 forms, or can be used as an edge to effectively loosen substance from the floor of an oven.

A truss structure, comprising the inclined parts 26 and 27 having the outer ends thereof secured to the rear face of the plate 18 and the transverse part 28 secured to both I beams

is interposed between the head and the ram.

The latticed stem described combined with the trussed head described provides rigidity in the stem so that the same does not bend or flex excessively laterally when, for instance, one side of the head encounters heavier resistance than the other.

The trussing of the head also prevents the head from being dislocated in its relation to the stem.

75 The latticed and trussed ram provides desirable rigidity through light weight structure and consequent saving in power required to move the ram.

The shafts 29 and 30 are journaled in the framing of the pusher at the front and rear ends thereof respectively.

The shaft 29 carries the flanged wheels 31 and 32 for contact on the bottom of the I beams to vertically support and laterally 85 guide the ram at the front end of the framing and also carries the sheave wheel 33 for the cable 34.

The shaft 30, located at the rear end of the framing, carries flanged wheels designated as 36 and similar to the wheels 31 and 32 on the shaft 29 for contact on the bottom of the I beams to vertically support and laterally 95 guide the ram at the rear end of the framing and also carries the sheave wheel 37 for the cable 34.

The shaft 38 is journaled in the forward or front end of the framing and carries the flanged wheels 39 and 40 for contact on the top of the I beams to vertically confine and 100 laterally guide the ram at the front end of the framing.

The shaft 41 is journaled in the rear end of the framing and carries the flanged wheels 42 and 43 for contact on the top of the I 105 beams to vertically confine and laterally guide the ram at the rear end of the framing.

The shaft 44 is journaled on the framing and is operated through suitable gearing by the motor 45 controlled by the rheostat 46 in 110 the cab and carries the driving sheave wheel 47 for the cable.

The cable 34 extends over the sheave wheels 47, 33 and 37 and has the threaded eyebolt 48 on one end thereof extending through the bracket 49 secured to the ram and also has the threaded eyebolt 50 on the other end thereof extending through the bracket 51 secured to the ram. The nuts 52 afford an easy means for adjusting the tension of the cable as well as the relation of the cable to the ram.

115 This cable end and bracket structure at once provides anchoring and adjusting means for the cable and on and in relation to the ram.

120 The cut out switch 53 is supported on the framing and has the free end operating arm 54.

The cut out blocks 55 are supported on the stem of the ram in suitable relation to the 125

free end of the arm 54 so that the same contacts this free end and move the arm and thereby cut out or shut off electricity to the motor to automatically stop movement of the ram 5 when the same reaches the end of a desired stroke or movement.

Upon rotation of the motor, in one direction, after the pusher has been moved to a position opposite or in front of an open oven, 10 the cable is moved longitudinally and thereby moves the ram longitudinally forward.

During this movement of the ram, the bottom of the head first slides along on or moves 15 over the top of the bench 23 according to the vertical adjustment of the bottom of the head and then slides along on or moves over the floor of the oven according to the vertical adjustment of the bottom of the head in relation to the floor.

20 During this movement of the head over the floor in the oven, the edge 25 cuts loose whatever substance may adhere tightly to the floor and the head pushes substances out of the oven.

25 The rigidity and trussed and latticed structure of the ram prevents distortion of the ram and promotes more efficient removal of substance from the oven.

When the ram has reached the end of its 30 forward stroke, the cut out block 55 contacts the arm 54 and moves the same for cut out or shut off of power to the motor and thereby automatically arrests further movement of the ram in the same direction.

35 An operator can, of course, control this movement of the ram through the rheostat 46.

Upon rotation of the motor in the opposite direction, the head is moved out of the oven. The switch 52 and the cut out block 55 can 40 be duplicated on the other end of the pusher device to operate the cut out switch as described above to stop the outward movement of the ram when the same reaches the end of its stroke.

45 As mentioned above, I am aware that my invention can be applied to different kinds of types of pushers. I am also aware that changes and modifications and substitutions can be made in the structure and arrangement 50 of elements or parts shown and described within the spirit and intent and scope of my invention and the appended claims; therefore, without limiting myself to the precise application of my invention as shown and described nor to the precise structure and arrangements of elements or parts as shown and described;

I claim:

55 1. In a pusher for a retort oven, a head 60 adapted to enter and travel in retort ovens, a straight stem on said head and guided on said pusher, a power means to move said stem and thereby move said head, said stem being of less width than said head to minimize the width of the pusher and comprises

ing two longitudinally parallel parts, lattice members holding said parts together and oppositely inclined for lateral strength and rigidity and light weight and to keep the stem straight for guidance thereof, strut and 70 gusset members between each of said longitudinal parts and said head to retain said head in correct relation with said stem during operation thereof in the retort oven, and said head having a part on the bottom thereof adjustably mounted to adjust the bottom of the head in relation to the bottom of the retort.

2. A pusher for retort ovens including a 75 longitudinally reciprocal ram having a head adapted to enter retort ovens and composed of two vertically related parts, the lower one of said parts being adjustable vertically to align the bottom of said head with a floor of an oven, and a guided stem on said head 80 longitudinally of said ram.

3. In a pusher for retort ovens, a reciprocal ram, a head on said ram, an oven floor scraping member on said head, said floor scraping member being adjustable on said 85 head for adjustment thereon to adapt the pusher for different heights of oven floors independently of other parts of the pusher.

In testimony of the foregoing, I affix my 90 signature.

EUGENE W. SCHELLENTRAGER.
